UNITED STATES PATENT OFFICE

FRANK ARENA, OF WATERTOWN, MASSACHUSETTS

DESIGN FOR A BOTTLE

Application filed June 2, 1932. Serial No. 43,959. Term of patent 3½ years.

To all whom it may concern:

Be it known that I, FRANK ARENA, a citizen of the United States, residing at 817 Mount Auburn St., city of Watertown, in the county of Middlesex and State of Massachusetts, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

FRANK ARENA.
